[57] CLAIM

The ornamental design for a chain-weighted tarp, as shown and described.

DESCRIPTION

FIG. 1 is a top, front and left side perspective view of a chain-weighted tarp showing my new design, the wheels shown in broken lines are for illustrative purposes only and form no part of the claimed design;

FIG. 2 is a top plan view thereof;

FIG. 3 is a bottom plan view thereof;

FIG. 4 is a front elevational view thereof, the rear being a mirror image thereof;

FIG. 5 is a right side elevational thereof, the left side being a mirror image thereof;

FIG. 6 is a top plan view of a chain-weighted tarp showing a second embodiment of my new design;

FIG. 7 is a bottom plan view of FIG. 6;

FIG. 8 is a fragmentary, top plan view of FIG. 6, with parts broken away illustrating the chain weight; and,

FIG. 9 is a fragmentary, bottom plan view of FIG. 6, with parts broken away illustrating the chain weight.
